PUNCHING MACHINE

Casimir L. Werk, Jr., Cincinnati, Ohio

Application July 3, 1933. Serial No. 678,882

10 Claims. (Cl. 164—112)

My present invention is an improvement upon the invention shown, described and claimed in my copending application for Letters Patent on Improvement in punching machines, filed in the United States Patent Office July 10th, 1930, as Serial No. 466,920, which has matured into Patent Number 1,928,680.

It is the object of my invention to provide a novel office machine for punching paper and the like, for use, for instance, in an identification system. Instancing such identification system, it may be assumed that a letter of credit is issued to a certain person for a given amount, and that the letter of credit has holes therein, which holes are located therein in selective positions to correspond with the identifying data, and the key therefor, furnished to the probable payers of the letter of credit, as more fully explained in my aforesaid copending application.

It is the object of my invention to provide improved means whereby to locate selector bars, and to hold the same in selected positions, by novel means resisting great punching strains; further, to provide novel slide bars for the selector bars which are exceptionally strong and durable and readily movable; further, to provide novel mounting means for the latter; further, to provide novel means whereby to hold the selected selector bars in selected positions after the punching operation has been begun in order to complete the desired punchings according to the original selections of the selector bars; further, to provide novel mounting means for the punches; and further, to provide novel clearing means for the slide bars.

My invention consists in novel means for accomplishing these various purposes, and in the novel parts and novel construction, arrangement and combinations of parts hereinafter described and claimed.

The invention will be further readily understood from the following description and claims, and from the drawings, in which latter:

Fig. 1 is a plan view of my improved device, partly broken away, for better illustration of parts.

Fig. 2 is a horizontal section of the same, taken in the plane of the line 2—2 of Fig. 3, and partly broken away.

Fig. 3 is a vertical cross-section of my improved device, taken in the plane of the line 3—3 of Fig. 1.

Fig. 4 is a vertical section of my improved device, taken in the plane of the line 4—4 of Fig. 1.

Fig. 5 is a vertical section of a detail of the

clearing mechanism, taken in the plane of the line 5—5 of Fig. 4.

Fig. 6 is an enlarged sectional detail view of the mounting for a punch, taken on the line 6—6 of Fig. 3.

Fig. 7 is a perspective view, partly broken away, and partly in section, showing the mounting of a selector key bar, and one of the slide bars in association therewith.

Figs. 8, 9, 10 and 11 are front elevations, partly in section, and partly broken away, and with the cover removed, showing successive positions of a selector bar and a slide bar in association therewith, and successive relations of the punch frame, the slide bar and the arresting means for the slide bars.

Fig. 12 is a perspective view of a detail of the mounting for the slide bar.

Fig. 13 is a bottom view, showing the pan for holding the punchings, partly broken away.

Fig. 14 is a vertical section, taken in the plane of the line 14—14 of Fig. 1, showing operating means for the punch frame; and,

Fig. 15 is a side elevational detail view, with the cover removed, and partly broken away, showing the relations of the punches, slide bars and locking means for the latter.

The frame of my improved device comprises a base 21, from which posts 22, 23 extend upwardly. The posts are fixed in bearings 24 in the base.

The base is preferably in the form of a trough comprising a bottom 25 and a marginal flange 26. The parts for operating the punch are located in the trough. The bottom of the trough is provided with an opening 27, closed by a pan 28, hinged to the base by hinges 29, and held in closed position by a spring latch 30, pivoted to the base on a screw 31 and received under a keeper 32 on the pan. The pan receives the punchings.

A frame 35 has bearings 36 at its respective corners about the posts 22, 23 and is slidable up and down on said posts. It has outer marginal depending flanges 37 and suitable cross-ribs for strengthening the same. The punch frame normally rests on the base, there being coacting lugs 38, 39 respectively on flanges 40 on the base and on the flanges 37, at the respective corners of the base and punch frame.

A die-plate 45 is fixed to the punch frame by means of screws 46. The die-plate is provided with a series of rows of punch holes 47 complementary to the junior punches hereinafter described, and with a master punch hole 48, com-

plemental to the master punch hereinafter described. (Fig. 3.)

In the present exemplification the die-plate is shown as the movable one of the complementary pair of punching parts, the punch being exemplified as the relatively stationary member of the cutting pair, although either member of the cutting pair, or both members of the cutting pair may be movable, and the positions of the punches and dies may be reversed, without departing from the spirit of my invention stated in the accompanying claims.

The means exemplified for operating the die-plate comprise a pair of rocker-rods 51, 52, which are shown of cornered cross-section. The rocker-rod 51 has a journal extension 53 screwed thereto, as at 54, and journaled in a bearing 55 in the base. The other end of this rocker-rod has a reduced extension 56, about which there is a journal sleeve 57, journaled in a bearing 58 in the base. The rocker-rod 52 has journal extensions similar to the journal extension 53, at its respective ends, journaled in bearings at the ends thereof in the base. (Fig. 14.)

The rocker-rods are at each of their ends provided with levers 61, 62, which rock therewith, these levers having holes corresponding in cross-section to the cross-section of the rods, so that the arms rock with the rods. The respective pairs of levers comprise arms 63, 64, which have a joint between them, as by means of a shoulder screw 65 received through a slot 66 in the arm 63, and threaded into a threaded hole in the arm 64. This causes combined movements of the levers. (Figs. 1, 3 and 4.)

An operating handle 68 is fixed to one of the rocker-rods, as to the reduced extension 56 of the rocker-rod 51, the operating arm being fixed thereto by a set-screw 69. This operating arm is provided for manual operation of the machine, although connections for power operations thereof may be provided.

Arms 71, 72 of said levers have connection with the punch frame for reciprocating the same, as providing said arms with slots 73, 74, pins 75, 76 on the punch frame being located in said slots for transmitting rocking movements of the levers into reciprocating movements of the punch frame. Suitable cushioning means are provided for cushioning descent of the punch frame.

The die plate 45 is provided with ledges 77 overhanging the flanges 26 of the base for preventing pinching of the fingers of the operator between the die-plate and the base.

A punch frame 81 has a series of punches 82, and a master punch 83 therein. The punches 82 may be termed junior punches. They are arranged in rows, preferably of ten punches each, a suitable number of rows being provided, of which there may be twelve, as an example.

The punch frame comprises a skeleton frame 84, a plate 85 at the top of the latter secured thereto, as by screws 86, and a plate 87 at the bottom of the frame, secured thereto by screws 88. (Figs. 3 and 4.) The plates are provided with registering holes 89, 90, in which the punches are guided in axial directions. The master punch is guided in similar holes correspondingly shaped for the master punch. (Fig. 6.)

The punches comprise a reduced punching shank 91, having the cutting end 92, these cutting edges coacting with the cutting edges of the punch holes in the die-plate for cutting the sheet. The punch has an upper shank 93 of

larger diameter, which reciprocates in the hole 89, and forms a shoulder 94 between the two shanks of different diameters of the punch.

The shoulder is normally at a level with the lower face of the plate 85. An eyelet 95 is received about the reduced shank of the punch, and is seated against the shoulder 94. The eyelet is forced upon the reduced shank. It has an outwardly extending annular flange 96, which forms a shoulder for one end of the spiral spring 97, about the reduced shank of the punch, the other end of this spring being seated by the upper face of the punch plate 87. The flange of the eyelet limits upward movement of the punch by striking the plate 85. (Fig. 6.)

The master punch may be similarly formed and may have similar guiding connections in the plates 85, 87, and be provided with a similar shoulder, and have a similar eyelet received similarly thereto, and a spring 98 between the eyelet and the plate 87 for normally retracting the master punch. (Fig. 3.)

This forms a substantial, cheap and effective means for mounting the punches and for instantly returning the punch out of its punching position, and to cause the punches to be effectively moved axially so as to maintain their upward positions, determined by the positions of the respective selector bars.

There is a sheet receiving space 101 between the die plates 45 and the plate 87 formed, for instance, by strips 102, 103, the inner edges of which form gaging edges for positioning the sheet between said plates, so as to cause registry of the sheet in correct relation in said space for punching the holes therein in correct positions. The plates 45, 85, 87, the gage strips 102, 103, and the frames 35, 84 are rigidly secured together by screws 104 for causing all of these parts to move together when operating the operating handle. The post 23 is a short post located under the space 101. (Figs. 4 and 8.)

Selector means are provided for selecting which of the punches in the series of punches are to be operated, and in the present exemplification tripping or clearing mechanism is provided in each of the rows of selector parts, so that when one of the selector parts in any row is operated, the balance of the selector parts therein are released. The selector parts are arranged in rows complementary to the punches in the respective rows of punches.

The selector parts are exemplified as bars 108. These bars are arranged to be placed in coactive relations with the respective punches of the series of punches. They are shown mounted in a selector frame 109 provided with bearings 110 at three of its corners received about the upper ends of the posts 22 and fixed to said posts, as by set-screws 111. Guide bars 112, 113 are secured respectively to the upper face and to the lower face of the frame 109, as by means of screws 114 passing through registering apertures in said bars and in the frame, nuts 115 being threaded to said screws for clamping the parts together. (Figs. 1, 2, 3, 4 and 7.)

The bars 112, 113 are provided with notches 116, 117, in which the bars 108 are guided and reciprocate. The walls of said notches and the edges of the adjacent bars form the guides for said shanks.

Helical springs 121 are received about the shanks. The lower ends of said helical springs bear upon the bars 113, their upper ends being resisted by washers 122 surrounding said bars. (Fig. 150)

Pins 123 received through said bars locate said washers and limit upward movements of the bars, by contact with the lower faces of the bars 112.

The bars 108 are provided with lugs 124, which

5 are pressed laterally from the body of said bars and form shoulders 125. The bars 108 extend through holes 126 in the upper walls 127 of slide bars 128. The lower ends of the lugs 124 have outer inclined faces 129. These lugs are arranged 10 to be pushed through the holes 126 by operation of a selective key 130 in order that the lugs may be positioned under said upper wall for holding the selector bar downwardly in selected position. (Figs. 8-11.)

15 The holes 126 are respectively sufficiently wide to permit the body of the selector bar and said lug to pass therethrough, thereby moving the slide bar endwise while the lug is passing through the hole, the slide bar being automatically retracted 20 when this lug has passed through said hole for placing one wall of the hole in obstructing relation with the lug to hold the lug and the selector bar in down position.

The slide bars are provided with depending 25 flanges 131 at their respective margins, forming the slide bars substantially U-shaped in cross-section, thereby making a very substantial structure. (Fig. 12.)

30 The slide bars are arranged side by side in the machine, as exemplified in Figs. 2 and 4, and are arranged to be moved independently and freely endwise, so that actuation of any slide bar will not produce actuation of any other slide bar, and insuring independent movement of all 35 of the slide bars.

The respective slide bars are provided with slots 134 at their respective ends, through which shanks 136 of hooks 137 are received. These hooks are presented in opposite directions, as 40 shown in Fig. 3, and are so placed as to reach under the upper wall of the slide bar to sufficient extent to support the slide bar in all of its relations. (Fig. 12.)

These shanks and hooks extend from the inner flanges 133 of channel bars 139, secured to 45 the selector frame. The channel bars have outer depending flanges 140, 141. (Fig. 3.)

Each of the slide bars has a helical spring 142 attached thereto, one end of the helical 50 spring being received through one of the slots 134 in the slide bar and the other end of the helical spring being secured to the outer depending flange 141. These springs act to normally urge the slide bars in one direction, toward the 55 side of the selector bars at which the selector lugs are located, so that the lower inclined faces of said lugs may automatically move the respective slide bars to permit passage of said lugs, the springs automatically returning the slide bars 60 to normal positions for placing their upper walls 127 above the lugs 124, which have been depressed so as to locate the selector bars in selective positions.

The depressing of any one of the selector bars 65 108 in a row of selector bars moves the slide bar for that row laterally so as to move all of the obstructing walls of the holes 126 therein laterally out of engagement with any of the lugs 124 which may have been thereunder, for releasing all of said selector bars which may have been 70 previously depressed in said row, the slide bar immediately retracting for locating one of its end walls of said holes above the lug of the selector bar, which is momentarily depressed, for retaining said depressed selector bar in depressed

position, and insuring that only one of said selector bars in any one row thereof shall remain in depressed position, it being assumed that only one of said selector bars is depressed at a time.

Any selector bar in each of the rows may be thus depressed and remain in depressed position, the depressed selector bars being those which control the operation of the punches for producing the identifying holes in the letter of credit or other sheet placed in the machine.

The depending flanges 131 of one of the slide bars 128 form contact parts arranged to contact the master punch 83, (Fig. 15), and to be in contact position throughout all punching operations, so that the master punch will punch at each punching operation.

The slides 128 are held in down position by having their upper faces contact the shoulders 143 on the inner depending flanges 138 of the channel bars 139 (Fig. 12). The channel form of the slide bars insures rigidity of said slide bars to resist punching stresses throughout their lengths resisted by said shoulders at their respective ends, and permits the selector bars and 100 the keys to be placed in close association for compact structure and arrangement.

There is a tendency for slide bars of this character to shift endwise on account of the narrowness of the shoulder 125 of the lug 124, or of any 105 shoulder of like nature which is moved under a slide bar to position a selector bar during the punching operation. This has been an objection to punching machines employing devices of this nature.

I have avoided this objection by providing locking means for the slide bars which move into coaction during approach movements between the punch plate and the punches, which locking means are in locked association when 115 the punching strain is imparted to the slide bar, for maintaining the punching parts in punching relation until the punching is completed.

A stop 151 is mounted on the punch frame. 120 It is shown as a plate 152, provided with a flange 153, and secured to the punch frame by screws 154. The flange extends across the ends of all the slide bars. The slide bars are provided with coacting stops 155. These are shown as one of 125 the ends of the slide bars. The flange is normally positioned in a plane beyond the ends of the slide bars when the latter are in retracted or normal position, and it is normally located outside the paths of movements of the slide 130 bars.

The movements of the slide bars and the locking relation of the stops are exemplified in Figs. 8 to 11 inclusive. Fig. 8 represents the normal relation of the parts, with the slide bar in retracted position and the punch frame in lowered or unpunching relation, the slide bars being free to move above the flange.

Fig. 9 represents the position of the slide bar while a key is being depressed with the lug 124 of the selector bar passing through the hole 126 in the slide bar, thereby shifting the slide bar endwise. This shifting moves the end of the slide bar to a position above the flange.

Fig. 10 represents the lug as having passed 145 through the slot in the slide bar and the slide bar having automatically retracted to locate the lug under the end wall of the slot for holding the selector bar and its key downwardly in constant relation with the punch when the punch 150

frame is raised, otherwise the positions of the slide bar and flange are the same as in Fig. 8.

Fig. 11 represents the parts in substantial punching relation, the punch frame having been 5 raised so that the end of the punch contacts the end of the selector bar for placing stress upon the slide bar and causing the piercing end of the punch to project into the sheet space 101 in the punch frame for piercing the paper, the punching 10 stress being placed upon the selector bar and the slide bar. Approach movement between the punch frame and the selector frame will, however, have moved the flange 153 into obstructing 15 relation with all of the slide bars, so that none of the slide bars can move endwise to release any of the selector bars, insuring that the punchings take place according to the selections by the keys. The stops move into coacting relations prior to the exertion of force in punching, so 20 that by the time the punching takes place the stops will have been in coacting relation to prevent disarrangement of the selected parts.

A full-clearing device is provided, exemplified as comprising a clearing bar 155, which is received against shoulders 156 on the slide bars formed by end rabbets 157 in one of the ends of the slide bars. This clearing bar has upwardly extending end arms 158, forming it a U-shaped structure. The upper ends of these arms are 30 pivoted on shoulder screws 160 threaded into the selector frame. A clearing key 161 has a shank 162 extending therefrom, and is pinned by pins 163 to a bell crank lever 164, pivoted by a shoulder screw 165 to the selector frame. The 35 shank 162 extends through a slot 166 in the cover 167. (Figs. 2, 3, 4 and 5.)

A link 168 is pivoted to the bell crank lever by a shoulder screw 169, and is pivoted to one of the end arms of the clearing bar by a shoulder screw 170. The clearing bar is normally retracted by a spring 171, whose respective ends are attached to the clearing bar and to the flange 141, lugs 172 on the clearing bar striking the posts 22 for limiting retraction of the clearing 45 bar.

Depressing the clearing key 161 moves the clearing bar for shifting all of the slide bars endwise, and moving all of the shoulders of all of the slide bars away from all of the lugs of all 50 of the selectors keys which may be in depressed positions, for causing all of the selector bars and their keys to rise into normal positions. The clearing bar is retracted to normal position as soon as the selector key is released.

The cover 167 is secured at three of its corners to the longer posts 22 by means of screws 173. The cover has depending walls 174, and is provided with a slot 175 at its front and one of its sides, registering with the space 101 for the 60 reception of the sheet to be punched. The corner post 23 does not extend into the sheet space.

The cover is provided with an opening 181 for exposing the key-board 182. The keys are fixed 65 to the outer ends of the selector bars. The keys correspond in number and value with the punches.

The punch frame and its connected parts are normally retracted by the weight of the parts.

When the proper keys have been depressed, the sheet to be punched is slipped through the slot 175 into the space 101, the rear edge of the sheet being brought into registry with the rear gage 102 and the side of the sheet being brought into 75 registry with the side gage 103. The operating

arm 68 is thereupon depressed, which, through the intervention of the levers 61, 62, raises the punch frame, and all of the punches thereon which have no obstructing selector parts 108 in coactive relation therewith.

The punches which have obstructing selector parts 108 placed in obstructing relation therewith, are prevented from moving upwardly with the punch frame, the die-plate 45 forcing the sheet past the punching ends of the punches thus obstructed, for piercing the sheet and providing the same with holes corresponding in position and relation to the punches which have been thus obstructed by the selector parts complementary to the actuated keys.

The master die opening in the die-plate and the punching end of the master punch are preferably oblong for providing the sheet with a master hole or slot.

Upon retraction of the operating arm, the die-plate and punch frame are retracted for freeing the sheet from the punches.

My improved device is compact and durable, and the operating parts are so made and related as to resist great strains.

Having thus fully described my invention, what I claim as new and desire to secure by Letters Patent, is:

1. In a punching machine, the combination of a base, a punch frame reciprocable on said base, normally retracted punches therein, a selector frame, normally retracted selector bars for said respective punches therein, keys for said selector bars, means for placing said selector bars in obstructing relations with said punches, 105 shafts of cornered cross-section, journals releasably secured to said shafts, bearings in said base for said journals, levers having holes of cornered cross-section in which said respective shafts are located for causing said respective 110 shafts and said levers thereon to rock together, pivot means connecting the proximate ends of said levers, pivot means connecting the outer ends of said levers and said punch frame for moving said punch frame, and operating means 115 having connection with one of said shafts.

2. In a punching machine, the combination of a row of punches including minor punches and a major punch, a row of selector bars for said minor punches, said respective minor punches 125 and selector bars being in endwise relation to each other, a channel shaped slide bar between said rows, means normally retracting said slide bar, said slide bar having side walls and a cross wall provided with holes in which said respective 130 selector bars are located, the proximate ends of said selector bars and said minor punches received between said side walls and said side walls located in obstructing relation with said master punch, said selector bars having projections slanting at one end and forming shoulders 135 at their other end coacting with one of the walls of said respective holes for respectively shifting said slide bar endwise and being received in locking relation with said slide bar, a punch 140 plate, and means causing approach between said punch plate and selected one of said minor punches and selector bars and punching relation between a selected one of said selector bars and a selected one of said minor punches and 145 between said side walls of said slide bar and said major punch for causing selected punching by said minor punches and definite punching by said major punch.

3. In a punching machine, the combination of 150

- a punch frame, punches arranged in rows therein, a selector frame, selector bars arranged in corresponding rows therein, channel shaped slide bars for said respective rows of selector bars, said respective slide bars having side walls and a cross wall provided with holes for said respective selector bars, said respective selector bars provided with projections whose lower ends are inclined and whose upper ends form shoulders coacting with the walls of said holes for locking said selector bars in depressed positions for coacting with said respective punches, means normally retracting said slide bars, the end portions of said slide bars provided with slots, stationarily positioned depending hooks extending through said slots and under said cross walls for slidably supporting said slide bars, and means normally retracting said slide bars.
4. In a punching machine, the combination of a punch frame, punches arranged in rows therein, a selector frame, selector bars arranged in corresponding rows therein, channel shaped slide bars for said respective rows of said selector bars, said slide bars having side walls and a cross wall provided with holes for said respective selector bars, said respective selector bars provided with locking means coacting with the walls of said holes for locking said respective selector bars in depressed positions for coaction with said respective punches, the respective end portions of said slide bars provided with slots, flanges depending from said selector frame at the respective end portions of said slide bars, said last-named flanges provided with separated hooks which extend through said slots and have end portions extending lengthwise of said slide bars for supporting said slide bars and forming shoulders at the upper ends of said hooks for the upper faces of said slide bars for slidably supporting said slide bars between said shoulders and said end portions of said hooks, and means normally retracting said slide bars.
5. In a punching machine, the combination of a punch frame, punches arranged in rows therein, a selector frame, selector bars arranged in corresponding rows therein, slide bars for said respective rows of selector bars, latching means between said respective selector bars and said slide bars for latching said respective selector bars in coactive relation with said respective punches, an end lock for said respective slide bars, and means whereby to cause approach between said punch frame and said selector frame for punching relation between them, said end lock mounted for positioning the same in locking relation with said slide bars during the approach between said frames.
6. In a punching machine, the combination of a punch frame, punches arranged in rows therein, a selector frame, selector bars arranged in corresponding rows therein, slide bars for said respective rows of selector bars, latching means between said respective selector bars and said slide bars causing momentary endwise movements of said slide bars, locking means for said slide bars normally out of range of said endwise movements, and means causing approach between said frames for punching action, said locking means mounted for being positioned during said approach into locking relation with said slide bars for locking said slide bars against such endwise movements during such punching action.
7. In a punching machine, the combination of a punch frame, punches arranged in rows therein, a selector frame, selector bars arranged in corresponding rows therein, slide bars for said respective rows of selector bars, said slide bars respectively having depending side walls and an upper cross wall provided with holes for the respective selector bars, said respective selector bars provided with projections whose lower ends are inclined and whose upper ends are located, means normally retracting said slide bars, said selector bars provided with projections one of whose ends are inclined and the other of whose ends form shoulders coacting with the walls of said holes for respectively moving said slide bars endwise for release of other selector bars latched by said slide bars, and for latched relation of said depressed selector bar by retraction of said slide bar, an upwardly extending flange on said punch frame at one of the ends of said slide bars, said slide bars normally movable above said flange, and means for causing approach between said frames for punching action by said punches and simultaneous locking relation between said flange and said slide bars, thereby retaining said slide bars in latched relations with said selector bars during such punching action.
8. In a punching machine, the combination of a punch frame, punches therein, said punch frame comprising a pair of separated plates, aligned holes in said plates, the holes in one of said plates being of greater diameter than the holes in the other of said plates, said punches having portions of larger diameter and stems of smaller diameter having a shoulder between them, eyelets about said stems having laterally extending flanges at one of their ends coacting with said shoulders and with said plate having said holes of greater diameter, spiral springs about said eyelets and said shanks between said last-named flanges and said plate having said holes of smaller diameter, the outer ends of said shanks formed with punching edges, said punch frame further comprising a punch plate rigid therewith and provided with punch holes in alignment with said first-named holes, there being a sheet space between said plate having the holes of smaller diameter and said punch plate, selector means for said punches, and means causing approach between said punch frame and said selector means.
9. In a punching machine, the combination of a punch frame, punches arranged in rows therein, a selector frame, selector bars arranged in corresponding rows therein, channel shaped slide bars for said respective rows of selector bars, said slide bars respectively having depending side walls and an upper cross wall provided with holes for said respective selector bars, said respective selector bars provided with latching means coacting with the walls of said holes for locking said respective selector bars in depressed positions for coaction with said respective punches, means normally retracting said slide bars, one of the ends of said slide bars provided with aligned rabbets, a clearing bar extending crosswise of said slide bars located in said rabbets, a clearing key therefor for moving said slide bars in unlatching direction, and means normally retracting said clearing bar.
10. In a punching machine, the combination of a punch frame, punches arranged in rows therein, a selector frame, selector bars arranged in corresponding rows therein, channel shaped slide bars for said respective rows of selector bars, said slide bars respectively having depending side walls and an upper cross wall provided with holes for the respective selector bars, said respective selector bars provided with projections whose lower ends are inclined and whose upper ends are located, means normally retracting said slide bars, said selector bars provided with projections one of whose ends are inclined and the other of whose ends form shoulders coacting with the walls of said holes for respectively moving said slide bars endwise for release of other selector bars latched by said slide bars, and for latched relation of said depressed selector bar by retraction of said slide bar, an upwardly extending flange on said punch frame at one of the ends of said slide bars, said slide bars normally movable above said flange, and means for causing approach between said frames for punching action by said punches and simultaneous locking relation between said flange and said slide bars, thereby retaining said slide bars in latched relations with said selector bars during such punching action.

ends form shoulders coacting with the walls of said holes for locking said selector bars in depressed positions for coaction with said respective punches and arranged for releasing all other selector bars in said respective rows in which given selector bars are so depressed, means normally retracting said respective slide bars, said side walls provided with end rabbets in cross

alignment with each other, a clearing bar in said rabbets coacting with one of the end walls thereof, means normally retracting said clearing bar, and a clearing key having operative connection with said clearing bar for moving said clearing bar in clearing direction and thereby moving all said slide bars in unlatching direction. 80
